UNITED STATES PATENT OFFICE

2,472,308

SEGMENTAL CHUTE FOR LOADING MATERIALS

James O'Halloran, Quebec, Quebec, Canada, assignor to Anglo-Canadian Pulp and Paper Mills Limited, Quebec, Quebec, Canada, a corporation of Quebec

Application February 10, 1947, Serial No. 727,644
In Canada December 17, 1946

5 Claims. (Cl. 302—14)

1

This invention relates to materials loading chutes, and more particularly to chutes adapted to guide and direct pulpwood or the like into a stowage space.

An object of the invention is to provide a loading chute for pulpwood and like materials which is adapted to receive such materials from a flume or conveyor and to distribute it efficiently in a stowage space, such as a ship's hold, so that maximum use is made of such space.

The invention resides generally in the provision of a segmental chute composed of a plurality of sections connected in overlapping relation to each other for relative horizontal and vertical movement, in association with hydraulic means for propelling materials through the chute.

The invention will be described with reference to the accompanying drawings, in which

Figure 1 is a sectional elevation of the chute,
Figure 2 is a plan view,

Figure 3 is a partial end elevation,

Figure 4 is an enlarged detail view in section of the associated hydraulic means,

Figure 5 is an enlarged end elevation of the hydraulic means,

Figure 6 is an enlarged sectional elevation of the connections between the sections, and

Figure 7 is an enlarged bottom plan view showing the section connections.

The chute is illustrated as associated with a flume 1, such as is adapted for conveying pulpwood, but it will be understood that it may be employed in conjunction with other types of conveyors, mechanical or otherwise.

The chute includes a stationary section 2 mounted on any suitable frame 3 and comprising a flat bottomed straight-sided member downwardly inclined, as shown, and having its mouth portion curved as at 4 to promote ease of flow from the conveyor thereinto. If used in conjunction with a flume, the bottom of the section 2 is formed as a grating 5 which permits discharge therethrough of the materials conveying water of the flume. The first section 6 of the segmental portion of the chute overlaps the outer face of the end portion of the section 2 and is hinged thereto for relative vertical swinging movement by means of a piano type hinge having portions 7 fixed to a bar 8 mounted on the end of section 6 and portions 9 fixed to a bar 10 pivotally mounted on the under side of section 2, a rod 11 passing through the portions 7 and 9 providing the pivotal connection. The pivotal mounting of the bar 10 is effected by means of a pin 12 carried by the bar and extending upwardly into a fitting 13

2

mounted on section 2 and to which the pin is secured as by a nut 14. This pivotal connection between sections 2 and 6 permits relative horizontal movement of section 6.

5 Each of one or more additional segmental sections 15 overlaps the outer end face of the adjacent section and is connected thereto for relative horizontal and vertical movement. As shown in Figures 6 and 7, a piano type hinge provides 10 for the vertical swinging movement and comprises a bar 16 fixed to the under side of the outer section having portions 17 pivotally engaging a rod 18 and a bar 19 pivotally mounted on a pin 20 carried by the inner section and having portions 21 pivotally engaging the rod 18. The pivotal mounting of the bar 19 on the pin 20 provides for the horizontal swinging movement.

The hydraulic means for propelling materials along the chute comprise a jet, or preferably a 20 pair of jets 22 carried by the section 6 and located at the outlet end of section 2. The jets are mounted on a cylindrical header 23 suspended by means 24 from the lower surface of section 6 and curve upwardly from the rear side of the header 25 through the bottom of the section and then forwardly along the upper surface of the bottom to a point adjacent the end of section 2. The under sides of the jets are spaced a slight distance above the bottom of the chute section to prevent undesirable spreading of water issuing therefrom and consequent loss of energy.

The jets are of flattened oval shape to provide a widened stream of water issuing therefrom. A protective cover plate 25 is provided for each jet.

35 The line of travel of water from the jets follows the same general direction as the axis of the section 6, but each jet is set so that the streams of water therefrom converge slightly towards a point slightly short of the end of the final section 40 in the chute. Such convergence of the jets provides better acceleration of the materials than if the streams of the jets were parallel throughout the travel thereof.

Water under pressure is supplied to the jets through a pipe 26 leading into a header 27 which is connected to header 23 by means of a plurality of flexible hose connections 28 which provide the necessary flexibility for movement of section 6.

Referring to Figure 3, section 6 of the chute has 50 a substantially flat bottom and vertical sides where it overlaps the section 2. From that point downwards, the cross section of section 6 and succeeding sections 15 transforms uniformly to a rounded bottom with rounded and higher sides. The cross section of the chute also tapers in-

wardly towards the discharge end so that the cross section at the end is approximately parabolic in shape. The chute is so designed since the wood or other materials tend to roll towards the center of it which gives the water jets the maximum opportunity to strike and accelerate the materials.

Any suitable means may be provided to impart vertical and horizontal movement to the chute. As shown, cables 29 connected to the end of the chute may be employed to raise and lower the chute and cables 30 also connected to the end of the chute may be employed to swing the same from side to side. Any suitable power means, not shown, may be employed to actuate the cables.

The chute described is particularly effective in directing a stream of pulpwood or the like under pressure to various points as desired to efficiently stow the same.

What is claimed is:

1. A loading chute for materials comprising a plurality of overlapping chute sections, and means connecting the overlapped sections for relative vertical and horizontal swinging movement comprising a bar mounted on the rearward end of each section, hinge portions carried by the bar, a second bar pivotally carried by the forward end of the adjacent overlapping section and having complementary hinge portions, and a rod pivotally engaged by all said hinge portions.

2. A loading chute for materials comprising a plurality of overlapping chute sections, means pivotally connecting each pair of overlapped sections for relative vertical and horizontal swinging movement, and hydraulic means carried by the first section for impelling materials through the chute, the entrance end of the chute being in cross section relatively wide with a substantially flat bottom portion and vertical side portions, the outlet end of the chute being in cross-section relatively narrow with curved bottom and side portions defining a substantially parabolic shape, said chute transforming gradually in shape from the entrance end to the discharge end.

3. A loading chute for materials comprising a 45 plurality of overlapping chute sections, means pivotally connecting each pair of overlapped sec-

tions for relative vertical and horizontal swinging movement, and hydraulic means for impelling and directing materials through the chute comprising a pair of jets carried by the first section, a header carried by said first section and to which said jets are connected, a second header, flexible connections providing communication between the headers and permitting relative movement of the first header with respect to the second header, and means for supplying water under pressure to the second header.

4. A loading chute as defined in claim 3 wherein the outlets of said jets are spaced slightly above the bottom surface of said section, and wherein said jets are inclined in directions converging towards each other to provide convergence of the streams of water issuing therefrom.

5. A loading chute for pulpwood or the like comprising in combination with a loading flume, 20 a stationary section extending laterally of the flume and having a curved entrance end for engagement with the flume, the bottom of said section comprising a grating to permit discharge therethrough of wood-conveying flume water, a first section in overlapping relation with the stationary section, at least one additional section in overlapping relation with a preceding section, means pivotally connecting each pair of overlapped sections for relative vertical and horizontal swinging movement, and a plurality of high pressure water jets carried by the first section and extending through the end portion of said grating, said jets being directed towards the outlet end of the chute.
